PATTERN CUTTER

Filed Jan. 14, 1926

Fig. 1.

Patented July 24, 1928.

UNITED STATES PATENT OFFICE.

HERMAN E. HOELZEL, OF ELMHURST, ILLINOIS.

PATTERN CUTTER.

Application filed January 14, 1926. Serial No. 81,329.

This invention relates to devices for cutting paper patterns to the designed shape for the garment trade, and its object is to provide a novel device of this kind which operates efficiently.

5 A further object of the invention is to provide an apparatus for the purpose outlined which is exceedingly simple in construction and therefore inexpensive to manufacture.

10 Another object of the invention is to provide a device of the character contemplated which may be operated with a minimum amount of skill and with safety.

15 With these objects in view, and any others which may suggest themselves in the description and claims to follow, a better understanding of the invention may be had by reference to the accompanying drawing, in

20 which

Figure 1 is an elevation of the device as viewed from the rear or remote side;

Figure 2 is an enlarged section taken on the line 2—2 of Fig. 1; and

25 Fig. 3 is a plan view of a regulating device.

Referring specifically to the drawing, 5 denotes a long wood board which is designed to form the base of the device. The latter is of a portable nature and is therefore capable of being mounted on any work table and fastened down or not, as desired.

Upon the base 5 is mounted a long metal support 6 having standards 7 and 8 at its ends. Between the standards are disposed two long shafts 9 and 10, these being vertically spaced and parallel. At one end the shafts 9 and 10 are journaled in the standard 7, and inside of the latter the shafts 40 carry meshing gears 9^a and 10^a whereby the shafts are geared for motion in opposite directions. The shaft 9 extends through the standard to receive a large gear 11 which in meshing with a pinion 12 carried by an electric motor 13 mounted on the base 5, provides reduced speed for the shafts.

The driving mechanism described above is grouped at one end of the base; and the operating or cutting mechanism is also grouped, at the opposite end of the base, whereby to leave the space between the shafts 9 and 10 unobstructed for a long distance, for a reason soon to become evident.

55 The standard 8 is supplemented in an upward direction by a transverse plate 14, which has a horizontal top bend 14^a and

forms with the standard 7, a support for a long bracing strip 15, suitable securing devices 16 being applied to hold the strip in place. A terminal downbend 15^a of the strip forms a bearing for the corresponding end of the shaft 9, while the standard 8 forms a like bearing for the shaft 10.

In line with the plate 14, the shafts carry staggered circular cutters 9^b and 10^b, respectively, of the bevel type, and these overlap with their contiguous surfaces midway between the shafts, as indicated in Figure 2. A work support or table 17 is disposed at the working level of the cutters 9^b and 10^b, a slot 18 being cut in the table to clear the cutters and that part of the plate 14 adjacent thereto. The table is substantially rectangular, and is rounded to form vertical or sloping sides 17^a which fit the sides and the end of the base 5 and are suitably attached thereto.

In operating the device, the current is turned on by means of a suitable switch, whereby to cause the cutters to turn in the 80 directions denoted by arrows in Figure 2.

The pattern sheet is then rested on the table 17 and fed through the cutters from the left toward the right, according to Figure 2. It will be noted that the front edge of the plate 14 is fashioned to follow the form of the cutters, whereby to provide a narrow guard 14^a at the issue-point of the cut. This guard separates the divided sections of the pattern sheet, so that they will not again move into 90 the path of the cutters and become damaged. The guard is made narrow in order to allow lateral freedom to the cut sections as the pattern sheet is swung to one side or the other along the path of the design. In this connection, it will be seen that the long horizontal space between the shafts 9 and 10 is provided to accommodate the pattern sheet and permit the same to swing freely irrespective of size.

100 In order that the pattern may not bulge as fed to the cutters, or feed irregularly, a regulating device is provided. As shown more clearly in Figures 2, and 3, this device mainly comprises two superposed rollers 18 and 19 between which the pattern sheet is passed before it is fed to the cutters. The roller 18 is journaled in the table, projecting slightly above the same through a slot 20; and the roller 19 is supported at its ends by 110 two bracket arms 21 whose opposite ends are carried by a spindle 22. The latter is

journalized in ears 23 projecting from a plate 24, such plate being mounted upon the bracing strip 15. On the plate is mounted a leaf spring 25, which projects in a forward direction to press on a lug 26 carried by the spindle 22 and thereby hold the roller 19 down on the pattern sheet. The roller exerts sufficient pressure on the latter to maintain it in flat condition and provide uniform feeding. The lug 26 is rectangular in form, so that when the roller 19 is raised high to permit the pattern sheet to be laid, as indicated by dotted lines in Figure 2, the spring 25 will press another side of the lug and maintain the roller in raised position. The securing devices 16 also serve to hold the plate 24 to the bracing strip 15 and are supplemented by securing device 16^a to facilitate the fastening of the spring 25.

20 An appliance is thus had which is simple in construction, easy to handle and operate, and capable of use as a portable or stationary machine, as desired. It is preferable, also, to provide an additional bearing for the shafts 9 and 10 in the form of an inner bearing standard 7^a.

15

25

I claim:

1. A pattern cutter comprising a base, a power source at one end thereof, a work table at the other end, shafts leading from the power source to the work table, cooperating rotary cutters mounted on the shafts in the region of the work table, and a separating guide for the work at the issue point thereof from the cutters, such guide following the profile of the cutters where the work issues whereby to part and shield the same during the courses of its progress.

2. A pattern cutter comprising a base, a power source at one end thereof, a work table at the other end, shafts leading from the power source to the work table, cooperating rotary cutters mounted on the shafts in the region of the work table, superposed rollers receiving the work on the way to the cutters, a pivoted hanger for one of the rollers, and adjustable to maintain the rollers in and out of contact, and a spring retainer for said hanger to lock it in the positions corresponding to such adjustment.

In testimony whereof I affix my signature.

HERMAN E. HOELZEL,
